ELECTRIC ROTARY LAUNDRY IRON

Alfred F. Yoerg, Des Moines, Iowa, assignor of
one-half to Harry Schlesinger, Des Moines,
Iowa

Application August 20, 1935, Serial No. 37,001

6 Claims. (Cl. 219—25)

An object of my invention is to provide a rotary iron for laundering, pressing and the like, which is simple, durable and comparatively inexpensive to manufacture.

5 A further object is to provide a tool having a heated sole plate which revolves relative to the major portion of the tool for the purpose of traveling over a much greater area of the material being ironed, or otherwise finished, during 10 normal movement of the tool across the material, thus reducing the amount of manual movement required in proportion to the actual passage of the sole plate over the material.

15 Still a further object is to provide a compact iron comprising a casing having a manipulating handle, a rotary sole plate mounted on the bottom thereof and an electric motor carried by the casing and connected with the sole plate for rotating it during the operation of the iron.

20 Still another object is to provide collector ring and brush means within the casing for electrically connecting the heating element of the sole plate with a current conducting cord which extends to the casing.

25 Another object is to provide a counterbalance means for the iron which is operable to assist the operator in moving the iron to a position spaced from the work when it is desirable to do so.

With these and other objects in view my invention 30 consists in the construction, arrangement and combination of the various parts of my device whereby the objects contemplated are attained, as hereinafter more fully set forth, pointed out in my claims and illustrated in the accompanying drawing in which:

Figure 1 is a rear elevation of a rotary laundry iron embodying my invention and showing it in ironing position.

Figure 2 is an enlarged plan view of the iron.

40 Figure 3 is a still more greatly enlarged view taken on the line 3—3 of Figure 2 to show internal details of construction.

Figure 4 is a sectional view on the line 4—4 of Figure 3 to show a collector ring and brush mechanism for supplying electric current to the heating element of the sole plate.

Figure 5 is a sectional view on the line 5—5 of Figure 1 showing a lock for a suspension cord connected with the iron; and

50 Figure 6 is a wiring diagram of the motor and heating element of my invention.

On the accompanying drawing I have used the reference numeral 10 to indicate a sole plate. It is circular in shape, being preferably upturned 55 at its periphery as indicated at 12. An annular

groove 14 is formed in the sole plate 10 within which I locate an electric heating element 16.

The heating element 16 is retained in position by a sheet of insulation 18 and a cover plate 20. Cap screws 22 are provided for retaining the cover plate 20 in position and clamping the sheet of insulation 18 between the cover plate and the sole plate.

The plate 20 has a tubular extension 24 in which is mounted a pair of graphite bearings 26. 10 These rotate on a stationary shaft 28 having a head 30 and mounted as by screw threading or the like in a hub 32 of a casing 34. Thus the sole plate 10 is rotatably mounted relative to the casing 34. 15

Mounted on the casing 34 is a motor 36. A gear casing 38 is connected with the motor 36. Within the gear casing the shaft of the motor has a worm 40 which meshes with a worm gear 42. The worm gear 42 drives a shaft 44 journaled in the casing 38. 20

A torsion spring 46 has its upper end connected with the shaft 44 and its lower end connected with a pinion shaft 48. The pinion shaft 48 is secured in a sleeve 50 which rotates in graphite 25 bearings 52. The bearings 52 are supported by a stationary sleeve 54 having a flange 56 secured to the upper surface of the casing 34 by screws 58. The sleeve 54 projects downwardly through an opening 60 in the casing. 30

Secured to the rotating sleeve 50 is a pinion 62 which meshes with a gear 64. The gear 64 is secured to the sleeve 24 whereby to rotate it, and thereby the sole plate 10, upon the pinion 62 rotating the gear. 35

Mounted within the casing 34 and suitably insulated with relation thereto are collector rings 66 and 68. Brushes 70 and 72 contact respectively with the collector rings 66 and 68 and are carried by terminals 74 and 76 of the heating element 16. 40 The brushes 70 and 72 are mounted on leaf springs 78 and 80 which cause the brushes to resiliently engage the collector rings.

For controlling the motor 36 I provide a motor switch 82 preferably of "snap-switch" type for 45 either turning the motor off or on as desired.

For controlling the heating element 16 I provide a rheostat switch 84, also preferably of the snap acting type and operable to energize the heating element 16 for low, medium or high heat, 50 as desired.

These are conveniently located adjacent a manipulating handle 86 which is mounted on the casing 34 by means of a yoke 88, a swivel stud 90 and a bracket 92. The stud 90 has an annular 55

groove 94. A retainer pin 96 extends through the bracket 92 for retaining the stud 90 in position, yet permitting swivelling movement thereof.

For convenience in positioning and supporting the iron, I provide the following described mechanism:

A pulley is provided having side plates 98 and a sheave 100 journalled therebetween. A suspension cord 102 extends over the sheave 100 and has one end secured to a yoke 104 and its other end to a counter-weight 106. The suspension cord 102 is preferably a combined suspension cord and electric conductor for conducting electric current from a plug-in fitting 108 or other connection with a source of electric current to the motor and heating element of the iron. The pulley may be suspended from a ceiling 110 or the like by means of a hook 112 or from a rigid arm or any other suitable type of support.

The pulley includes a clamp arrangement comprising an arm 114 pivoted on the sheave axle 116. The arm 114 carries a pivot pin 118 to which is pivoted a clamp block 120. The block is slotted at 122 to slide over a pin 124 carried by the side plates 98. The clamp block 120 includes a cam surface 126 which is shaped eccentric relative to the pin 118.

Practical operation

In the operation of my electric rotary laundry iron, the iron may be suspended when not in use by the cam surface 126 of the clamp block 120 squeezing the suspension cord 102 against a backing surface 128 of the arm 114. When it is desired to use the iron, the cord 102 is pulled downwardly slightly to release the cam surface 126 and swung toward the right in Figure 5 to the dotted position for causing the arm 114 to swing the clamp block 120 about the pin 124 as a pivot, thus completely releasing the cord 102 relative to the supporting pulley.

The iron is then moved downwardly into contact with the work (such as a piece of fabric 130 on an ironing board 132 in Figure 1) and the cord 102 pulled downwardly far enough to provide sufficient slack for the ironing operation. The cord 102 is then swung toward the left so as to rotate the clamping block 120 counterclockwise to the clamped position shown by full lines in Figure 5 so that the counter-weight 106 will not take up the slack during the ironing operation.

The counter-weight is preferably heavier than the iron and thus effectively relieves the operator of the necessity of lifting the weight of the iron when raising it from the work being done so that another piece of work can be placed on the ironing board.

The heating element 16 is readily controlled as to the temperature desired for the sole plate by manipulating the rheostat switch 84 while the rotation of the sole plate is obtained by switching the switch 82 to the "on" position. The sole plate 10 revolves for the purpose of causing a maximum sliding travel of the sole plate over the work being ironed with a minimum of manual operation in moving the iron relative to the work to cover the entire surface thereof. Thus the desirable sheen on ironed work is secured without the necessity of having to repeatedly move the iron across the same area. I have found that approximately 80 R. P. M. is best for the speed of rotation of the sole plate 10.

The swivelly mounted handle 86 facilitates

manual movement of the iron over the work, whereas a handle rigidly mounted relative to the casing 34 would sometimes be in an awkward position for ironing a particular part of the work. The torsion spring connection 46 provides for smoothness of operation especially when parts of the work offer more resistance to the rotation of the sole plate than other parts thereof, which tends to throw a greater load on the motor and which load is partly absorbed by twisting of the spring so that the operation of the motor is thus made smoother.

Some changes may be made in the construction and arrangement of the parts of my device without departing from the real spirit and purpose 15 of my invention and it is my intention to cover by my claims any modified forms of structure or use of mechanical equivalents which may be reasonably included within their scope.

I claim as my invention:

1. In an electric rotary laundry iron, an inverted, cup-shaped casing, a headed post depending from the top wall thereof, a current supply cord extending to said casing, a sole plate having a hub rotatably mounted on said post 25 and confined against vertical movement by said top wall and the head of said post, an electric heating element carried by said sole plate, collector ring and brush means for electrically connecting said heating element with said current supply cord and an electric motor operatively connected with said sole plate to rotate the same relative to the casing. 30

2. In a rotary iron of the character described, an inverted, cup-shaped casing, a manipulating handle member thereon, a post projecting downwardly from the top thereof, a sole plate, a hub projecting upwardly therefrom and rotatably receiving said post, electric means for heating said sole plate, collector ring and brush means for supplying electric current to said sole plate from said casing and an electric motor carried by said casing for rotating said sole plate. 35

3. In a rotary iron of the character described, a manipulating handle member, a sole plate, a heating element for said sole plate, a cover plate for retaining said heating element against said sole plate, means projecting upwardly from said cover plate for journaling said cover plate relative to said handle member and means for rotating said last means and thereby said sole plate, and heating element means for supplying electricity to said handle member and means for continuously supplying the electricity from said handle member to said heating element 50 during rotation thereof relative to the handle member. 55

4. In a rotary iron of the character described, a casing, a post projecting downwardly from the top thereof, a sole plate having a hub rotatably mounted on said post and serving as a bottom for said casing, means carried within said sole plate for heating it, an electric motor supported on said casing for rotating said sole plate relative to said casing, said means for heating said sole plate comprising an electric heating element, means for supplying electricity to said casing and means for continuously supplying the electricity from said casing to said electric motor and to said sole plate during rotation thereof relative to the casing. 60

5. In an electric rotary laundry iron, an inverted, cup-shaped casing, a headed post depending from the top wall thereof, a current supply cord extending to said casing, a sole plate 75

having a hub rotatably mounted on said post and confined against vertical movement by said top wall and the head of said post, an electric heating element carried by said sole plate, collector 5 ring and brush means for electrically connecting said heating element with said current supply cord and an electric motor operatively connected with said sole plate to rotate the same relative to the casing, said motor being mounted on said 10 casing with its shaft in a horizontal position, a gear casing connected with said motor and thereby supported, a vertical shaft projecting from said gear casing, an operative connection within said gear casing between said shafts and an operative connection between the lower end of said 15 vertical shaft and said sole plate.

6. In a rotary iron of the character described, a casing, a post depending from the top thereof, a sole plate having a hub rotatably mounted on said post, means for heating said sole plate and means for rotating said sole plate comprising a 5 motor mounted on the exterior of said casing, worm gearing connected therewith, a gear casing for enclosing said worm gearing and for supporting it, said gear casing being connected with said motor for support thereby, a vertical 10 shaft projecting downwardly from said gear casing and an operative connection from the lower end of said vertical shaft to said sole plate for rotating the sole plate upon rotation of the vertical shaft due to energization of said motor. 15
